UNITED STATES PATENT OFFICE.

THEODORE B. WILCOX, OF NEWARK, NEW JERSEY, ASSIGNOR TO FRANK E. GILBERT, OF NEW YORK, N. Y.

INHALER.

SPECIFICATION forming part of Letters Patent No. 351,677, dated October 26, 1886.

Application filed August 5, 1886. Serial No. 210,086. (No model.)

To all whom it may concern:

Be it known that I, THEODORE B. WILCOX, a citizen of the United States, residing at Newark, in the county of Essex and State of New Jersey, have invented new and useful Improvements in Vaporizers, of which the following is a specification.

My invention relates to improvements in inhalers or vaporizers having openings at both ends; and it consists in the combination, with two stoppers fitted to the openings, of a connecting-shank between said stoppers, so that the stoppers are simultaneously caused to open or close their respective openings. The shank is made of two connected sections with an interposed spring, so as to permit each stopper to be tightly inserted or pressed into its opening, regardless of differences in wear, all of which is more fully pointed out in the following specification and claims, and illustrated in the accompanying drawings, in which—

Figure 1 represents a vertical central section of a vaporizer provided with my improved stopper. Fig. 2 is a horizontal section of the same in the plane $x x$, Fig. 1. Fig. 3 is a sectional elevation, on a larger scale than the preceding figures, of the stopper detached. Fig. 4 is a vertical central section of a vaporizer provided with a modified form of the stopper. Fig. 5 is a similar section of a vaporizer having a removable bottom. Fig. 6 shows a side view of the bottom detached and the key for removing the same.

Similar letters indicate corresponding parts.

In the drawings, the letter A designates the cylindrical body or shell of the vaporizer, which is enlarged at one end to form a circular eye-cap, a . A bottom or partition, b , closes the end of the shell at the bottom of the eye-cap, in which partition is a central opening, B. The other end of the shell is contracted and has an opening, B', by which air may enter the shell. Within the shell is secured a cylinder of perforated sheet metal or wire-gauze, c , which leaves an unobstructed passage or chamber, C, and forms an annular space between the cylinder and the shell of sufficient size to contain an absorbent packing, D, which is saturated with any volatile substance of medical character, that will by evaporation and consequent application to

any part of the body stimulate the nerves and blood-vessels and produce a beneficial result.

The openings in the shell A register with the chamber C, and are closed when the vaporizer is not in use by stoppers E F, one for each opening. In the bottom or partition b of the shell is formed an internal screw-thread, which receives a thread on the stopper E, said stopper being suitably threaded and so formed that it can be readily grasped by the fingers and turned. The stopper F is adapted to bear upon a seat, f , surrounding the opening B', and the stoppers are connected by a shank, G, which, as shown in Fig. 4, is in one piece, so that when the stopper E is unscrewed the stopper F is simultaneously removed from its seat, and finally both stoppers can be removed from the chamber C when the vaporizer is to be applied, and air can freely enter the chamber. To provide for any unequal wear of the stoppers, which might cause one stopper to fit tightly to its seat before the other was down on its seat, I form the shank G in sections, as best shown in Fig. 1. The one section, g , is formed with a socket, into which extends part of the other section, g' , and a pin, h , thereof enters a slot, h' , in the section g . A spring, H, is placed within the socket, and is compressed by the section g' , thereby holding the stopper F against its seat. This arrangement allows the stopper E to be screwed upon its seat regardless of the stopper F, and consequently both stoppers always effectually close the openings B B'.

In the example shown in the drawings the stopper F consists of a washer, f , and a cap, f' , the washer being held to an enlarged portion of the shank-section g by said cap. The stopper E consists of a threaded body having a flanged portion and a washer, e , which closes against the partition b of the shell A, thereby forming a tight joint. The stopper F may, however, consist of a cone properly ground, as shown in Fig. 4, or the stoppers may have such other construction as will render them best adapted for their purpose.

To facilitate the removal of the absorbent packing and the substitution of new material, I provide a removable bottom or partition, b^* , which has a screw-thread that engages an internal thread in the shell A. A washer, b' ,

abuts against a seat in the casing and makes a tight joint. In this bottom is formed an internal thread for the reception of the stopper, as before, and two sockets, *j j*, are also therein, into which pins on a key, *J*, can be inserted, so as to remove or insert the said bottom. The perforated cylinder *C* is best secured at one of its ends to the removable bottom, so that as the latter is removed the cylinder is withdrawn from the case, and thus the packing can be readily removed.

I do not broadly claim herein an outer and interior cylinder having absorbent material interposed between them, with openings and corresponding stoppers at each end, as such forms the subject-matter of an application filed by me May 25, 1885, Serial No. 166,681.

What I claim as new, and desire to secure by Letters Patent, is—

- 20 1. In a vaporizer, the combination of a shell, *A*, an internal cylinder, an absorbent packing surrounding the cylinder, openings in the shell registering with the cylinder, stoppers fitted to said openings, and a connection between said stoppers for simultaneously moving both stoppers to open or close their respective openings, substantially as shown and described.
- 25 2. In a vaporizer, the combination of a shell, *A*, an internal cylinder, an absorbent packing surrounding the cylinder, openings in the shell registering with the cylinder, stoppers *E F*, controlling said openings, and a sectional shank connecting the stoppers, substantially as shown and described.
- 30 3. The combination, with an atomizer comprising a shell, *A*, having end openings, *B B'*, and an internal cylinder, *c*, of the two end stoppers, *E* and *F*, a connecting-shank composed of two sections, *g g'*, and a spring, *H*,

interposed between the said sections, substantially as described.

4. The combination, with an atomizer comprising a shell, *A*, having end openings, *B B'*, and an internal cylinder, *c*, of the two stoppers *E* and *F*, a connecting-shank composed of two sections, *g g'*, one having a socket into which the other extends, a spring, *H*, located in the socketed section, and a pin-and-slot connection between said sections, substantially as described.

5. The combination, with an atomizer comprising a shell, *A*, having a top opening, *B'*, an internal cylinder, *c*, a removable and replaceable bottom, *b**, for the shell, having a central opening, *B*, two stoppers, *E* and *F*, adapted to the said top opening, *B'*, and the opening in the removable and replaceable bottom, and a shank connecting the stoppers for simultaneously opening and closing both stoppers, substantially as described.

6. In a vaporizer, the combination of a shell, *A*, having an opening at one end, an internal perforated cylinder, an absorbent packing surrounding the cylinder, a removable bottom 65 for the shell, a threaded opening in said bottom, and two stoppers, *E* and *F*, connected by a shank for operating both stoppers to open and close both said openings, one stopper having a thread engaging the thread in the bottom of the shell, substantially as shown and described.

In testimony whereof I have hereunto set my hand in the presence of two subscribing witnesses.

THEODORE B. WILCOX.
